(57) **CLAIM**

The ornamental design for a treadmill, as shown and described.

DESCRIPTION

FIG. 1 is a top, front, and left perspective view of a first embodiment of the treadmill showing our new design.

FIG. 2 is a front view of the treadmill of FIG. 1.

FIG. 3 is a rear view of the treadmill of FIG. 1.

FIG. 4 is a left side view of the treadmill of FIG. 1.

FIG. 5 is a right side view of the treadmill of FIG. 1.

FIG. 6 is a top view of the treadmill of FIG. 1.

FIG. 7 is a bottom view of the treadmill of FIG. 1.

FIG. 8 is a top, front, and left perspective view of a second embodiment of the treadmill.

FIG. 9 is a front view of the treadmill of FIG. 8.

FIG. 10 is a rear view of the treadmill of FIG. 8.

FIG. 11 is a left side view of the treadmill of FIG. 8.

FIG. 12 is a right side view of the treadmill of FIG. 8.

FIG. 13 is a top view of the treadmill of FIG. 8; and,

FIG. 14 is a bottom view of the treadmill of FIG. 8.

The broken line showing of portions of the treadmill in FIG. 3 depicts environment and forms no part of the claim. The shade lines in the figures show contour, not surface ornamentation and form no part of the claimed design.

1 Claim, 14 Drawing Sheets
